UNITED STATES PATENT OFFICE.

HAROLD W. BROWN AND ALLEN E. BAILEY, JR., OF SCHENECTADY, NEW YORK, AS
SIGNORS TO GENERAL ELECTRIC COMPANY, A CORPORATION OF NEW YORK.

VIBRATORY DEVICE.

Application filed July 28, 1925. Serial No. 46,686.

Our invention relates to electrically operated vibratory devices and has for its object the provision of a vibrator having a low frequency of vibration.

Our invention has various applications to devices requiring vibratory motion, such as bells, intermittent brakes, etc. It has particular application to indicating devices or other members which have a tendency to spin at high speed, in which connection it may be used to apply a brake intermittently to the indicating member in such manner that spinning is prevented, although the member is free to move between the applications of the brake to a correct indicating position.

In carrying out our invention we provide a magnet coil which is energized periodically and an armature operated by the coil, together with means for causing the armature to move to different positions periodically when the coil is energized. When the coil is energized from an alternating current source, the armature may be in one position during one half of a current cycle and in its other position during one or more succeeding half cycles.

For a more complete understanding of our invention reference should be had to the accompanying drawing, Fig. 1 of which shows in diagrammatic form a vibratory device embodying our invention as applied to the braking of a motion receiving device; while Fig. 2 is a diagrammatic view of the motion receiving device.

Referring to the drawing, our invention in one form comprises a magnet coil 10 which is mounted on a U-shaped magnet core 11, which is arranged to be energized intermittently by suitable means. It may, for example, be energized from an alternating current supply source 10a. The magnetic circuit through the core 11 is completed by means of a movable armature 12 made of magnetic material which is mounted on a spring 13. As shown, the spring 13 has its upper end secured at 14 near the center of the armature, and its lower end secured to a short adjustment member 15 which is pivotally secured at one end to the core 11 at 16, and has its other end adjustable about the pivot 16 by means of a screw 17. This screw 17 cooperates with a tapped hole in the core 11 and passes through an aperture in the free end of the

member 15. A helical spring 18 is provided between the member 15 and the core 11 whereby the member 15 is pressed outward against the head of the screw 17.

It will be observed that the armature 12 has a pivotal motion, permitted by the flexing of the spring 13, toward and away from the core 11. The adjustment of the member 15 is such that the spring 13 tends to swing the armature away from the core against a stationary spring 19, forming a stop for the armature in its position most remote from the core 11. The spring stop 19 consists of a resilient bar which is secured at its lower end to a supporting member 20. Its position can be adjusted by means of a screw 21 in the support bearing against it at a point somewhat above its fixed end, and its freedom toward the support 20 can be regulated by means of stop screw 22.

Mounted on the core 11 is a resilient bar spring 23 having one end fixed to the core and its free end extending into the path of the upper end of the armature 12 as it approaches the core. This spring 23 is relatively heavy as compared with the springs 13 and 19, and is strong enough to prevent the armature from being pulled up to its position nearest the core unless the armature has first been accelerated from its most remote position designated by the stop spring 19. In other words, the pull of the magnet coil on the armature due to magnetic attraction is not great enough by itself to bend the spring 23 appreciably, but when the armature has been accelerated from its position against the stop 19 its energy of motion in addition to the pull of the magnet coil is sufficient to overcome the spring 23. The increased magnetic attraction when the armature has been brought up close to the core by the bending of the spring 23 is sufficient to retain the armature in this position momentarily when the current is at or near its maximum instantaneous value.

On the lower end of the armature 12 is fixed an arm or extension 25 which carries a brake pad 26 secured on the end of a flexible arm 27. This brake pad engages one side of an indicating dial 28 when the armature 12 is pulled up by the magnet coil. As shown, the dial is mounted on the shaft 29 of a motion receiving device 30 so as to be driven by the motion receiving device. This motion receiving device is of a type comprising

ing a polycircuit armature winding 31 (Fig. 2) and a field winding 32 which is supplied from a source of alternating current. It will be understood that the receiving device is 5 operated in accordance with motion applied to a transmitting device which is similar in construction, the two devices having their armature windings electrically connected. Receiving devices of this type have a tendency when suddenly accelerated to fall into step with the alternating current supply source applied to their fields and move at high speed as synchronous motors. By applying the brake pad 26 intermittently to 10 the dial 28 this tendency to spin is overcome, while, at the same time, the dial is free to turn between the applications of the brake pad to its correct indicating position. If the brake pad were applied with each alter- 15 nation of the alternating current supply impressed on the coil 10, in other words, each half cycle, the dial would have but a very short time in which to turn between the applications of the brake. The operation of 20 the vibratory mechanism is such, however, that the brake is not applied every half cycle.

The operation of the vibratory device is as follows: Upon the energization of the 30 coil 10 by a suitable source of alternating current, the armature 12, being then at rest against the stop 19, as shown in the drawing, will be pulled toward the core 11 and will compress the spring 23 upon striking it and 35 be pulled to its position of close proximity to the core. The armature will be strongly attracted to this position while the half current cycle which set it in motion is near its crest, but when the instantaneous current falls and approaches zero the armature will 40 be repelled violently by the heavy spring 23. By virtue of the repulsive action of the spring 23 itself acting against the magnetic attraction of the coil as the current builds 45 up in the opposite direction through the remaining half of the cycle, the armature is prevented from being pulled back toward the core during the next one or more half cycles. The acceleration imparted to the 50 armature 12 by the spring 23 also plays a large part in overcoming the attractive force of the magnet coil. The result is that the armature is thrown into engagement with the spring 19 and the spring compressed to 55 a certain extent depending upon its adjustment and its resiliency. As the spring recovers it tends to throw the armature back toward the coil and upon the occurrence of some subsequent half current cycle the armature is again attracted, as previously de- 60 scribed. It will be observed that a certain time interval is introduced while the armature is moving away from the coil both before and after its engagement with the 65 spring 19. The interval during which the

armature is actually in engagement with the spring 19 depends upon the resiliency of the spring and its adjustment by means of screws 21 and 22, and it may be sufficient to consume one or more half cycles in addition 70 to the time consumed in passing across the air gap. The total time consumed in one complete oscillation of the armature is equal to at least one complete cycle, i. e. two half cycles, and may be any greater number of 75 half cycles. The frequency of oscillation of the armature is thus equal to or less than the frequency of the supply source, whereas in previous devices the frequency of oscillation is twice the frequency of the supply 80 source. The armature is thus attracted to its position in close proximity with the magnet coil during one half of a current cycle and is released during one or more of the following half current cycles, and the brake 85 pad 26 is applied accordingly. This gives the dial an opportunity to turn between the applications of the brake.

The spring 19 has the function not only of 90 acting as a back stop but also of absorbing the energy of motion of the armature. By adjusting the screw 21 the spring 19 can be adjusted to vary the gap, i. e., the amplitude of vibration of the armature. The screw 22 is adjusted to suitably limit the 95 movement of the spring so as to prevent its breaking, and also to vary the absorption of energy by the spring. Various devices may be used in place of the spring 19 for absorbing the energy of the armature. The 100 arrangement shown, for example, may be adjusted for a setting which will cause the armature to be pulled up every other half cycle, it being thrown to its remote position during the intervening half cycles. 105

Although we have disclosed the magnet coil 10 as being intermittently energized by connecting it to an alternating current supply source, it may also be energized intermittently in various other ways, such as by 110 a pulsating direct current. In this case the direct current source of supply may be broken by movement of the armature in a well known manner. The armature would then be attracted to the magnet coil during 115 certain pulsations and repelled to its remote position during the intervening pulsations. 115

While we have described our invention as embodied in concrete form and as operating in a specific manner in accordance with the provisions of the patent statutes, it should be understood that we do not limit our invention thereto, since various modifications thereof will suggest themselves to those skilled in the art without departing from 120 the spirit of our invention, the scope of which is set forth in the annexed claims.

What we claim as new and desire to secure by Letters Patent of the United States is:

1. A vibratory device comprising a mag- 130

- net coil arranged to be energized intermittently, an armature movable toward and away from said coil from one position to another, and means for causing said armature to periodically occupy its position remote from said coil when the coil is energized whereby the frequency of vibration of said armature is reduced.
2. A vibratory device comprising a magnet coil arranged to be energized intermittently, an armature movable toward and away from said coil from one position to another, means for causing said armature to periodically occupy its position remote from said coil when the coil is energized whereby the frequency of vibration of said armature is reduced, and means for varying the interval of time that said armature occupies said remote position.
3. A vibratory device comprising a magnet coil arranged to be supplied with alternating current, an armature movable toward and away from said coil from one position to another, and means for periodically maintaining said armature in its position remote from said coil during certain half current cycles in said coil, said armature being moved to its other position by the magnetic attraction of said coil during the intervening half cycles.
4. A vibratory device comprising a magnet coil arranged to be energized intermittently, an armature movable toward and away from said coil from one position to another, means for biasing said armature to its position remote from said magnet coil, and means for throwing said armature periodically to a position remote from said coil when the coil is energized.
5. A vibratory device comprising a magnet coil arranged to be energized intermittently, an armature movable toward and away from said coil from one position to another, means for biasing said armature to its position remote from said magnet coil, means for throwing said armature periodically to a position remote from said coil
- when the coil is energized, and means for maintaining the armature in said remote position during a portion of the time 50 intervals.
6. A vibratory device comprising a magnet coil arranged to be energized intermittently, an armature movable toward and away from said coil from one position to another, means for biasing said armature to its position remote from said magnet coil, and resilient means compressed by movement of said armature toward said magnet coil for periodically throwing said armature to a 60 position remote from the coil when the coil is energized whereby the frequency of vibration of said armature is reduced.
7. A vibratory device comprising a magnet coil arranged to be energized intermittently, an armature movable toward and away from said coil from one position to another, a spring for biasing said armature to its position remote from said magnet coil, and a second spring engaged and compressed 70 by said armature when it approaches said magnet coil, said spring being arranged to throw said armature periodically to its position remote from said coil when the coil is energized whereby the frequency of vibration of said armature is reduced.
8. A vibratory device comprising a magnet coil arranged to be supplied with alternating current, an armature movable toward and away from said coil from one position 80 to another, a spring for biasing said armature to its position remote from said magnet coil, and a relatively heavy spring engaged and compressed periodically by said armature as it nears said coil during certain of 85 the half voltage cycles impressed on said coil, said armature being thrown away from said coil during the intervening half current cycles.

In witness whereof, we have hereunto set 90
our hands this 27th day of July, 1925.
